HYDRAULIC MACHINE

Eduard William Woydt, Stuttgart, Germany

Application December 15, 1949, Serial No. 133,069

Claims priority, application Germany
July 25, 1949

14 Claims. (Cl. 103—161)

1

The invention relates to hydraulic pumps and motors with cylinders radially arranged in a cylinder block in which the plungers or pistons are moved by eccentric members. In order to free the plungers in such machines of turning moments which are transmitted from the cylinder block on the eccentric member and vice versa, it is known to provide between the plunger and eccentric member a plate freely adjustable and to fix the position of the cylinder block to the eccentric member by couplings. In addition rollers between the plate and eccentric member help to prevent the transmission of lateral forces on the plungers. However, it was found that the very small swinging motions which the plate makes about the pin which connects it to the plunger, and which are unavoidable owing to the elasticity of the material, unfailingly cause friction oxidation. The arrangement of a single roller in the plunger or piston does not permit very high hydraulic pressures and results in a substantially larger structure. This is also the case when special "pots" are placed over the cylinders in order to take up the track pressures by the lateral forces. A thickening of the piston end to a crosshead for the purpose of taking up the track pressures does not lead to the goal. Such crosshead if the plungers or pistons had flanges inserted therein would have to be inserted with the same little play, however, with a larger diameter. This is first practically impossible and, second, would only result in excessive wear of the flanged-in crosshead instead of the piston.

The invention utilizes between each plunger or piston and coordinated swinging member a yielding member and accomplishes the freedom of the plungers from tangential forces or turning moments, respectively, by the following construction:

Cylinders radially arranged in a cylinder block; pistons slideable in the cylinders; at least one eccentric member cooperating with the pistons; between each piston and the eccentric member a member swingable about an axis parallel to the machine axis; between each piston and its swingable member a second member yielding transversely of the turning axis in such a manner that turning moments from the eccentric member through the yielding member owing to giving way of the yielding member are transmitted to the cylinder block and guideways or tracks embodied with the cylinder block and through which all lateral forces are transmitted which originate by the action of the eccentric member on the swingable member.

2

When the swinging axis of the swinging member coincides with the axis of the yielding member and the swinging member by the eccentric member pressure is far enough advanced so that its lateral rollers press on the guide track of the cylinder block, the yielding member rolls off the lower surface of the piston so that no lateral forces can act on the piston. For example, it can be ensured that forces acting in the direction of the plunger axis, or on both sides, in such a manner that the resulting force coincides with the plunger axis or approximates closely to the plunger axis. Hence forces acting in the direction of the plunger axis but transmitted beside the plunger axis to the plunger would produce a moment tending to incline the plunger, so that at the end of the plunger a force would occur in a lateral direction, and at another point a force in an opposite direction.

20 The invention has importance in like manner for pumps and motors with a rotary cylinder star, as well as for designs in which the cylinders are stationary. It is especially of importance for engines with lapped plungers, in which the 25 plungers travel within the cylinders without piston rings or the like, since such plungers wear rapidly and become leaky when lateral forces occur.

It is preferable to shape the yielding member 30 as a cradle which is swingable at least in one plane, which is perpendicular to the rotation axis of the machine.

Moreover the invention makes it possible to 35 create a machine occupying but little space. This purpose serves the fact that the yielding members react by rollers against the guide tracks. For it a hydraulic machine of the present kind works with a reduced stroke, the paths of the pistons are very short. If then the yielding members with sliding means reacted upon the 40 guide tracks, the danger of excessive wear on the guide tracks would exist unless the sliding means were of great length and in consequence take only a low specific load. Long sliding means 45 have a heavy weight. In contrast thereto, the invention further aims to keep the weight of all movable parts low.

The invention has the further object of constructing a liquid pump or motor of the kind 50 described with revolving cylinders in such a manner that the centrifugal forces of the pistons are taken up in a corresponding manner without exerting lateral components and that the friction losses of the pump or motor are kept low.

55 Further means for attaining the named aims

and further objects of the invention and the means for their realization are apparent from the following description of two embodiments and from the claims.

While both embodiments of the invention described hereinafter illustrate the eccentric member in the center of the cylinder block and the cylinders outwardly thereof, it is to be pointed out that the reverse arrangement is possible. In the first embodiment the centrifugal forces of the pistons are taken up by rings which are rigidly connected with two opposing plungers or pistons, while in the second embodiment the centrifugal forces of the plungers or pistons are taken up by freely rotating rings. Such freely rotating rings are known by themselves.

The invention is not limited to the described and illustrated embodiment, but relates to all similar embodiments in which the same or similar effect is attained by the means of the invention.

The accompanying drawings illustrate by way of example two embodiments of the invention, in which:

Figure 1 is a vertical sectional view through a pump constituting a first embodiment of the invention taken along lines 1—1 of Figure 4.

Figure 2 is a sectional view taken along lines 2—2 of Figure 1.

Figure 3 is a sectional view taken along lines 3—3 of Figure 1.

Figure 4 is a sectional view taken along lines 4—4 of Figure 1.

Figure 5 is a sectional view taken along lines 5—5 of Figure 1.

Figure 6 is a view similar to Figure 1 of a second embodiment of the invention and taken along lines 6—6 of Figure 7.

Figure 7 is a sectional view taken along lines 7—7 of Figure 6.

Figure 8 is a sectional view taken along lines 8—8 of Figure 7.

Figure 9 is a top plan view of a plunger and roller carriage assembly.

According to one example, as shown in Figures 1 to 5, the pressure member for cylinder block 101 of the pump is journaled at 102 upon a shaft 103 and formed as a hollow cylinder, within which an adjustable double eccentric member 104/105, and also the devices for transmitting the forces between the plunger and the eccentric member, are located. A plunger 106 is slidable in the cylinder 107, which extends, like the remaining cylinders, to the outside of the cylinder block 101, and is closed there by means of a closing screw plug 108. The plunger 106 has a cross-head 109, Figures 2 to 4, which is rigidly connected to a similar cross-head of the diametrically opposite plunger 110 by means of two rings 111, Figure 2, so that the plungers 106 and 110 are kept parallel to each other. Within the cross-head 109 there is a yielding member constructed as a rocker 114, which is movable by means of a cylindrical face upon the cross-head 109. Its straight line contacting with the cross-head 109 is perpendicular to the axis of the plunger, for example 110 and parallel to the axis of shaft 103. A roller carriage 116 is arranged at the sides of the rocker and guided perpendicularly to the guideways or tracks 118 in slots or cut outs 117 provided in the cross-head 109. These guideways are located on rings 119 and 120, which are rigidly connected with the cylinder block 101 on both sides of the plungers 106 and 110. A further pair of plungers with cross-heads 131 is arranged at right angles to the pair

of plungers 106, 110, and connected together by means of rings 132 in a similar manner to the cross-heads 109. They also carry a rocker 114, with a roller carriage 116. The latter, as shown in section on the line 1—1 (Figure 4), has some clearance, so that it is able to transmit freely the tangential pressure from the rocker 114 to the guideway or track 118. In order to reduce the friction there are rollers 122 on the pin 121 of the carriage, which bears only with its two ends against the rocker 114 by means of supporting surfaces 123. The rocker 114 is provided with a semi-circular recess 124, in which sliding shoes 125 shaped correspondingly are swingably journaled. The end 127 of the sliding shoes advancing in case of rotation is formed somewhat longer than the end 128, so as to facilitate the admission of oil below the sliding shoe. The plungers, for example 106 and 110, are screwed 20 into the cross-head 109 by means of a threaded pin 129, and are fitted with a slot 130 for inserting a screw-driver. The cross-heads 131 of the second pair of plungers are rigidly connected together through other rings 132, being adapted 25 symmetrically to that plane which is drawn on a level with the axes of all the plungers. The distance of the rings 132 from this star middle plane is smaller than the distance of the rings 111 of the pair of plungers 106, 110 from the same plane. Both the rings 132 are split at 112 (also the rings 111) and at the opposite side, whilst they are connected with each other by means of laps through bolts 113. In order to control the plungers, bores 133 are provided with 30 in the cylinder block 101, these bores communicating with two half-annual grooves 134 and 135 in the shaft 103. Supply and discharge will be effected through radial bores 136 and axial channels 137.

During operation the shaft 103, which carries the adjustable double eccentric member 104, 105, is stationary, whilst the cylinder block 101 rotates. Owing to the pressure between the eccentric member and the plunger there will be created a tangential component from the rocker 114 through the roller carriage 116 to the guideways 118, the carriers of which, i. e. the rings 119, 120, are rigidly connected with the cylinder block receiving the cylinders.

According to the second example of embodiment, shown in Figures 6—9, the resilient member, being constructed likewise as a rocker, is journaled in a roller carriage, which is supported in a multiple manner by means of rollers or sliding members, namely: primarily against the eccentric member, for transmitting the pressure of the plunger, secondarily against lateral guideways for transmitting the tangential forces, which might exert a lateral pressure upon the plungers, and thirdly against freely running rings, for transmitting the centrifugal forces of the plungers. By this manner a complete balancing of the plungers from lateral forces will be obtained, besides other advantages.

The numeral 201 designates the cylinder block, in which four cylinders 202 are located, the supply and discharge of which takes place through channels 203 communicating with annular grooves 204, 205 in the shaft 206 and connecting with supply and discharge channels 207 through bores 208 and 209. The block 201 rotates upon the shaft 206 carrying a double eccentric member 210/211, which may be adjusted in a manner not illustrated. Within the cylinders 202 travel plungers 212, fitted with cross-heads 213. The

latter are provided with round-shaped supporting surfaces 214, bearing against flat supporting faces 228 on a box-shaped carriage 215. Upon an axle 216 of this carriage there are wheels 217, which are able to come into contact with guideways 218 and 219. The diameter of the wheels 217 is less by about 16 mm. than the distance between the guideways or tracks 218 and 219. Furthermore the carriage 215 carries upon its axle 216 an oscillating frame 220, which is provided with four pairs of rollers 221, bearing against two freely running rings 222. The box-shaped carriage 215 receives a yielding member constructed as a rocker 223. This yielding member bears by means of a round-shaped supporting surface 224 against a flat face of the cross-head 213. Contact takes place in a straight line which is approximately perpendicular to the plunger axis. The rocker 223 is movable in a tangential direction to a small extent within the box-shaped carriage 215. It receives within a correspondingly cylindrical recess a cylindrical extension 225 of a roller carrier 226, the rollers of which travel upon the eccentric member 211, whereby there may be arranged between the rollers 227 and the eccentric member 211 a ring, not shown in the drawing, which is turnable upon the eccentric member 211. The oscillating axle of the roller carrier 226 coincides approximately with the axle 216 of the carriage 215, so that the axes of the wheels 217, the oscillating axle of the frame 220 and the oscillating axle of the roller carrier 226 coincide approximately. The effect thereupon is that all forces intersect at a point or on an axis, so that they partly compensate each other, and no lateral forces can be exerted upon the plungers 212.

Instead of the oscillating frame 220 with the rollers 221, two wheels of larger diameter may be provided, the axis of which coincides with the axis of the wheels 217, each of them running upon one of the rings 222.

It is therefore clear that this invention provides a hydraulic machine which is capable of operating as a pump or a motor. The machine as illustrated in the two embodiments essentially comprises a cylinder block 101 or 201. The shaft is within the cylinder block as illustrated at 103 and 206 and the shaft axis constitutes the axis of rotation of the machine. The illustrated cylinder blocks have radially arranged cylinder bores therein located radially outward of the shaft, some of which are shown at 107 and 202 in the respective modifications. Plungers are slideably mounted within the cylinders and eccentric means 104 and 105 in the first form of the invention and 210, 211 in the second form are mounted within the cylinder block for cooperation with the plungers. Swingable members respectively denoted at 125 and 226 in the two forms of the invention are interposed between each plunger and the eccentric means and these members are swingable about axes parallel to the axis of the shaft. Yieldable members denoted at 114 and 223 are positioned between each plunger and its associated swingable member. These yieldable members are yieldable or loosely movable in the direction transverse of each cylinder axis that is at right angles to the shaft axis. Roller means constituted by the roller carriage 116 in one form and the carriage 220 in the other form are operably associated with each plunger and influenced by movement of each yieldable member in the direction perpendicular to the plunger axis and transverse of the shaft

axis. Guide tracks are embodied within the cylinder blocks of each form of the invention and cooperable with the roller means for guiding the same. The guide tracks are disposed in planes parallel to the axis passing through each cylinder and longitudinal to the shaft axis. By the arrangement described, the force between the eccentric means and plunger is transmitted by and through the cooperation of the swingable members and the yieldable members. Each yieldable member has an arcuate face engaging its associated plunger in the form of Figures 1 to 5 so that the contact between the yieldable member and the associated plunger lies on a straight line extending perpendicular to the plunger axis and parallel to the shaft axis.

I claim:

1. A hydraulic machine capable of operating as a pump or motor comprising a cylinder block, 20 a shaft therewithin, the axis of which constitutes the axis of rotation of the machine, said cylinder block having radially arranged cylinder bores therein radially outward of the shaft, plungers slidably mounted within the cylinders, eccentric means within the cylinder block for cooperation with the plungers, swingable members swingable about axes parallel to the shaft axis and respectively interposed between each plunger and the eccentric means, yieldable members yieldable in 30 the direction transverse of each cylinder axis that is at right angles to the shaft axis, and respectively positioned between each plunger and its associated swingable member, roller means operatively associated with each plunger and influenced by movement of each yieldable member in the direction perpendicular to the plunger axis and transverse of the shaft axis, guide tracks embodied within the cylinder block and cooperable with the roller means for guiding the same, 40 said guide tracks being disposed in planes parallel to planes passing through the axis of each cylinder and longitudinally through the shaft axis and the force between the eccentric means and plunger being transmitted by and through the cooperation of the swingable members and the yieldable members.

2. In a hydraulic machine as defined in and by claim 1, wherein each yieldable member constitutes a cradle and means supporting the cradle 50 for swinging movement in at least one plane perpendicular to the shaft axis.

3. A hydraulic machine according to claim 1, wherein each yieldable member has an arcuate face engaging its associated plunger so that the contact between the yieldable member and associated plunger lies on a straight line extending approximately perpendicular to the plunger axis and parallel to the shaft axis.

4. A hydraulic machine as defined in and by 60 claim 1, in which the roller means includes a roller carriage operatively associated with each plunger, said guide tracks including two guide tracks for each carriage and each roller carriage being arranged with slight clearance relative to 65 its pair of guide tracks in the direction perpendicular to the plunger axis.

5. A hydraulic machine as defined in and by 70 claim 1, wherein the roller means constitute roller carriages, each plunger having a cross head thereon extending at least in the direction of the shaft axis and means operatively coupling each carriage with a cross head.

6. A hydraulic machine as defined in and by 75 claim 1, wherein each swingable member constitutes a sliding shoe cooperable with the eccentric

means, each shoe having an arcuate bearing surface radially spaced from the eccentric means and engaging the first mentioned bearing surface so that each yieldable member is swingable about an axis parallel to the shaft axis.

7. A hydraulic machine as defined in and by claim 1, wherein the plungers are arranged in pairs of opposing plungers and at least one ring rigidly connecting two opposing plungers.

8. A hydraulic machine as defined in and by claim 1, wherein the plungers are arranged as pairs of opposing plungers, a pair of rings rigidly connecting each pair of opposing plungers, both rings of the pair of rings connecting each pair of opposing plungers being arranged symmetrical to the plane containing the axes of all the plungers, one ring of each pair of rings lying in a plane being spaced longitudinally from one side of the plane containing the plunger axes and the other ring of each pair of rings lying in a plane spaced longitudinally from and on the opposite side of the plane containing the plunger axes.

9. A hydraulic machine as defined in and by claim 1, in which a cross head is provided on each plunger, a pair of longitudinally spaced freely running rings within the cylinder block, the roller means including a roller carriage operatively associated with each plunger, at least one roller carried thereby for cooperation with the guide tracks and additional rollers carried by each carriage and bearing against the rings, each cross head contacting a yieldable member and the respective cooperating contacting surfaces defining a line contact between each cross head and each yieldable member with the line contact extending approximately perpendicular to the axis of the associated plunger and parallel to the shaft axis.

10. A hydraulic machine as defined in and by claim 1, in which a cross head is provided on each plunger, a pair of longitudinally spaced freely running rings within the cylinder block, the roller means including a roller carriage operatively associated with each plunger, at least one roller carried thereby for cooperation with the guide tracks and additional rollers carried by each carriage and bearing against the rings.

11. A hydraulic machine as defined in and by claim 1, in which a cross head is provided on each plunger, a pair of longitudinally spaced freely running rings within the cylinder block, the roller means including a roller carriage operatively associated with each plunger, at least one roller carried thereby for cooperation with the guide tracks and additional rollers carried by each carriage and bearing against the rings, and each swingable member constituting a member movably engaging the eccentric means having a head thereon engaging an associated yieldable member, said head having an arcuate surface and each yieldable member having an arcuate socket to receive the head of its associated swingable member so that relative swinging movement between each yieldable member and its associated swingable member is facilitated.

12. A hydraulic machine as defined in and by claim 1, in which the guide tracks constitute spaced tracks extending parallel to and on opposite sides of each plunger axis, the roller means constituting a roller carriage operatively associated with each plunger including at least one roller for cooperative engagement with the guide tracks, a pair of longitudinally spaced freely running rings within the cylinder block, additional roller means on each roller carriage bearing against the freely running rings, and the axis of each roller means that engages the guide tracks being approximately coaxial with the respective axes about which the swingable members swing.

13. A hydraulic machine as defined in and by claim 1, including two freely running rings within the cylinder block, said roller means including a roller carriage operatively associated with each plunger, rollers carried by the carriage in cooperation with the guide track, a frame swingable about the axis of the last mentioned rollers and carrying additional rollers for cooperation with and bearing against the freely running rings, the swinging axis of each said frame coinciding approximately with the axis of swing of the swingable members which transmit force from the yieldable members to the eccentric means.

14. A hydraulic machine as defined in and by claim 1, and including two freely rotatable rings within the cylinder block, the roller means including a roller carriage operatively associated with each plunger, and each carrying at least one roller cooperating with the guide tracks, a swingable frame associated with each roller carriage for swinging movement about the axis of the roller that cooperates with the guide tracks, said frame carrying rollers thereon bearing against the freely running rings, the swingable member and yieldable member associated between each plunger and the eccentric means including arcuate engaging surfaces providing an axis about which the yieldable member and swingable member can move relative to one another, and the axis of each frame of the rollers engaging the guide tracks, and the axis about which the respective yieldable members and the swingable members move relatively to one another approximately coinciding.
